Attorney

UNITED STATES PATENT OFFICE.

IRA C. ELLIS, OF EAST ST. LOUIS, ILLINOIS.

LOCKING DEVICE FOR GEAR-SHIFTING LEVERS OF AUTOMOBILES.

1,215,509.

Specification of Letters Patent.

Patented Feb. 13, 1917.

Application filed July 8, 1916. Serial No. 108,216.

To all whom it may concern:

Be it known that I, IRA C. ELLIS, a citizen of the United States, residing at East St. Louis, in the county of St. Clair and State of Illinois, have invented certain new and useful Improvements in Locking Devices for Gear-Shifting Levers of Automobiles, of which the following is a specification, reference being had to the accompanying drawings.

This invention relates to an improved locking device for the gear shifting lever of an automobile and has for its primary object to provide simple and easily operated means for locking the lever in a neutral position and preventing its actuation by unauthorized persons.

It is also another object of my invention to provide a device of the above character wherein the several operating parts are entirely inclosed and protected against injury so that the device will at all times be effective and reliable in operation.

It is a further general object of the invention to produce a lever locking device for the above purpose, which is exceedingly simple in its construction and may be produced at relatively small manufacturing cost.

With the above and other objects in view, my invention consists in the novel features of construction, combination and arrangement of parts to be hereinafter more fully described, claimed and illustrated in the accompanying drawing, in which,

Figure 1 is a vertical sectional view through the lever, showing the same locked in its neutral position;

Fig. 2 is a section taken on the line 2-2 of Fig. 1, the locking dog being shown in its released position in dotted lines; and

Fig. 3 is a section taken on the line 3-3 of Fig. 1.

Referring in detail to the drawing, 5 designates the shaft which is operatively connected to the gear shifting clutches, and 6 a tubular lever having a hub or sleeve 7 formed on one of its ends surrounding the shaft 5. An opening 8 extends diametrically through the sleeve 7 and communicates with the inner end of the tubular lever 6. This opening registers with a similar opening 9 formed in the shaft 5. A rod 10, constructed in two halves or sections, is adapted to be engaged within the hollow lever 6, and these rod sections, at one of their ends, are exteriorly threaded, as at 11, for engage-

ment with complementary threads on the interior wall of the lever. The other ends of the sections of the rod 10 are of hollow, hemispherical form to provide a head or knob 12, the end of the lever 6 having a concave face, as shown at 13, constituting a seat for said head. The sectional rod 10 is longitudinally bored, as at 14, one end of said bore being enlarged as shown at 15. Through said bore and the coinciding openings 8 and 9 in the sleeve 7 and shaft 5, a locking rod 16 extends.

The spherical knob or head 12 is provided with a diametrically extending opening within which a lock casing 17 is suitably secured. The wall of one section of the hollow head 12 has an inwardly projecting lug 12' formed thereon engaged in a recess in one end of the lock casing 17, whereby the latter is properly supported in position. The other section of the head 12 is centrally formed with an opening in which the other end of the lock casing 17 fits. An annular flange 17' projects inwardly from the edge of the opening in the head 12 and seats in a peripheral groove in the lock casing. A rotatable barrel 18 is suitably mounted in said casing and is formed with a keyhole slot 19. The inner end of this barrel is provided with an angularly projecting lug 20 having a cam face 21 for bearing engagement upon one end of the rod 16. A coil spring 22 is arranged upon the rod 16 and within the larger section 15 of the bore in the rod 10, one end of said spring bearing against the inner end of the bore and the other end thereof against the collar 23 fixed to said rod. This spring normally acts to force the rod 16 outwardly and through an opening 24 in the lock casing 17 in which said rod is slidably engaged.

25 designates a plate having a bracket 26 thereon formed with a socket 27 to receive the other end of the locking rod 16.

For the purpose of securely holding the rod 10, against turning movement within the hollow lever 6, a set screw 28 is threaded in the lever for engagement in a recess formed in the periphery of the rod 10.

In the operation of the device, it will be understood that the owner of the automobile equipped with my invention may readily insert his key in the slot 19 and rotate the barrel 18 so that the cam face 21 of the lug 20 will bear upon the rod 16 and force the same downwardly against the action of the

spring 22 and into the socket 27 in the bracket 26. This lug, when moved to a position in axial alinement with the rod 16, effectually holds said rod against an upward movement and thereby retains the lever in its neutral position and locks the same against actuation so that the machine cannot be used by unauthorized persons. When the owner reverses the rotation of the lock barrel so as to disengage the lug 20 from the rod 16, the spring 22 will immediately act to force the rod upwardly out of the socket 21 and release the lever for operation, whereby the power transmission gears may be shifted as desired.

From the foregoing description, taken in connection with the accompanying drawing, the construction, manner of operation and several advantages of my invention will be clearly and fully understood. It will be seen that I have produced a very simple and serviceable device for securely locking the gear shifting lever of an automobile which, however, may be easily and quickly actuated to release the lever when it is desired to operate the machine. The several parts of the device are entirely inclosed and housed within the lever so that they are protected by the lever against the action of the elements and also from injury in the event of an accident. The device can, however, be easily and quickly disassembled and the several operating parts of the lock removed from the lever arm. These parts being all of very simple form can be readily replaced when necessary at nominal cost.

While I have shown and described the preferred construction and arrangement of the several detail features of the device, it is to be understood that the same are susceptible of considerable modification therein and I, therefore, reserve the privilege of adopting all such legitimate changes as may be fairly embodied within the spirit and scope of the invention as claimed.

Having thus fully described my inven-

tion, what I desire to claim and secure by Letters Patent is:—

1. The combination with a tubular gear shifting lever, of a longitudinally bored rod fitted within said lever, a locking rod operating in the bore of said first named rod, a keeper, a spring normally acting to hold said locking rod out of engagement with the keeper, and means mounted upon the outer end of said first named rod to co-act with the other end of the locking rod and project said rod into locking engagement with the keeper.

2. The combination with a tubular gear shifting lever, of a rod detachably fitted within said tubular lever and having a longitudinal bore, a keeper, a locking rod operating in said bore, a spring surrounding the rod and normally acting to yieldingly hold the same out of engagement with the keeper, and cam means mounted upon the outer end of said first named rod to co-act with the locking rod and project the same into locking engagement with the keeper.

3. The combination with a shaft and a tubular lever thereon, said shaft and lever having coinciding openings communicating with the inner end of the tubular lever, of a rod detachably fitted within said tubular lever and having a longitudinal bore to communicate with said openings, a locking rod shiftable through said bore and said openings, a keeper, a spring acting to normally hold the locking rod out of engagement with said keeper, said first named rod being provided with a spherical head on its outer end, and a rotatable cam mounted within said head to co-act with one end of the lever and project the other end thereof into locking engagement with said keeper.

In testimony whereof I hereunto affix my signature in the presence of two witnesses.

IRA C. ELLIS.
